US00D838262S

(12) **United States Design Patent** (10) **Patent No.:** **US D838,262 S**
(45) **Date of Patent:** **** Jan. 15, 2019**

(54) **CASE FOR A SMARTPHONE**

(71) Applicant: **OTTER PRODUCTS, LLC**, Fort Collins, CO (US)

(72) Inventors: **Kevin W. Witter**, Fort Collins, CO (US); **Dustin S. Rodriguez**, Fort Collins, CO (US)

(73) Assignee: **Otter Products, LLC**, Fort Collins, CO (US)

(**) Term: **15 Years**

(21) Appl. No.: **29/602,509**

(22) Filed: **May 1, 2017**

(51) LOC (11) Cl. **14-03**

(52) U.S. Cl. **USPC** **D14/250**

(57) **CLAIM**

The ornamental design for a case for a smartphone, as shown and described.

DESCRIPTION

FIG. 1 is a front isometric view of a case for a smartphone; FIG. 2 is a rear isometric view thereof; FIG. 3 is a front view thereof; FIG. 4 is a rear view thereof; FIG. 5 is a left view thereof; FIG. 6 is a right view thereof; FIG. 7 is a top view thereof; and, FIG. 8 is a bottom view thereof.

The dot-dash broken line represents a boundary of the claimed design. The dash-dash broken lines depict unclaimed subject matter. The broken lines and unshaded surfaces bounded by broken lines form no part of the claimed design.

1 Claim, 6 Drawing Sheets
